Primary Examiner — Paula Allen Greene*(74) Attorney, Agent, or Firm* — Muncy, Geissler, Olds & Lowe, P.C.**(57) CLAIM**

The ornamental design for a waveguide, as shown and described.

DESCRIPTION

FIG. 1 is a perspective view of a waveguide showing our new design;

FIG. 2 is a top plan view thereof;

FIG. 3 is a bottom plan view thereof; and,

FIG. 4 is a side plan view thereof.

The broken lines depict portions of the waveguide that form no part of the claimed design.
